UNITED STATES PATENT OFFICE.

ISAAC P. LAMBING, OF IONE, CALIFORNIA.

CENTRIFUGAL PUMP.

SPECIFICATION forming part of Letters Patent No. 367,919, dated August 9, 1887.

Application filed February 28, 1887. Serial No. 229,947. (No model.)

To all whom it may concern:

Be it known that I, ISAAC P. LAMBING, of Ione, Amador county, State of California, have invented an Improvement in Centrifugal Pumps; and I hereby declare the following to be a full, clear, and exact description of the same.

My invention relates to the class of centrifugal pumps; and my invention consists in the combinations of devices which I shall herein-after fully describe and claim.

The object of my invention is to provide a centrifugal pump in which there is no friction on the outer rim of the driver, and whose operation and power are purely centrifugal.

Referring to the accompanying drawings for a more complete explanation of my invention, Figure 1 is a horizontal section of the driver, taken on the plane of the peripheral discharge-slot a' , Fig. 2, and a plan of the receiving-casing. Fig. 2 is a vertical section of driver and receiving-casing.

A is the driver, consisting of the hollow circular piece or disk secured centrally to a shaft, C, by which it is rotated. The under central portion of the driver is provided with an inlet suction-aperture, a, working within the material to be pumped. The outer portion or rim of the driver is beveled or made with converging inclines, as shown in section in Fig. 2, and this beveled portion concludes with a short straight portion, in which is formed the peripheral slot or discharge-aperture a' , extending entirely around the driver.

Within the driver and arranged radially are the long partitions or diaphragms a^2 and the intermediate short partitions, a^3 . These extend centrally from near the outer rim of the driver, the former reaching to about the vertical plane of the discharge-aperture, while the latter extend but a short distance, as shown in Fig. 1. These partitions, both long and short, are made wedge-shaped, with the apex or thin portion pointing centrally, and this construction makes the space or chamber between them inclined or tapering the reverse way—that is to say, with its smallest portion outwardly—thus providing, in connection with the inclined walls of the driver, for a true nozzle shape.

B is the receiving-casing. It consists of an

annular tube or pipe, which is fixed in position outside of the plane of the driver and entirely separate therefrom, the two not coming in contact. This casing is preferably formed with a comparatively straight portion on its inner side, and has in said side, near the lower portion of it, a slot or opening, b, which extends all the way around it. This slot or opening is made funnel-shaped and tapering to inwardly, and the walls of the opening are preferably carried inward a short distance beyond the walls proper of the casing, as is shown in section, Fig. 2. This opening is directly opposite the peripheral opening in the driver when operating. From the casing extend the outlet-pipes b' , one or more in number, as the case may be.

The operation of my pump is as follows: A rapid rotary motion is imparted by suitable means to the driver. The material to be pumped is thereby sucked in through the inlet a, and by centrifugal force is thrown outwardly and radially into the several chambers of the driver and into their tapering nozzles, which are formed by the inclined rim of the driver itself and the wedge shape of the partitions, and out through the peripheral opening or slot a' . It emerges therefrom in an annular and continuous sheet or thin jet, and crossing the intervening space is thrown forcibly into the opposing opening b of the receiving-casing, and at all points of said opening in a continuous sheet or stream of an annular form. Its injection into and through said opening is of such force as to project it completely into the casing, thereby forcing out previous material therein through the discharge-pipes b' .

While a receiving slot or opening in the casing B of a straight form might be used, the funnel or tapering shape, as here shown, is preferable, as embodying and continuing the principle of the nozzles.

The object of extending the walls of the opening b a little within the casing is to better provide against the tendency of the water or other material to return through said opening. The object of the partitions a^2 and a^3 , long and short, alternating as described, is to provide for the nozzle shape of the outer ends of the chambers.

Having thus described my invention, what

I claim as new, and desire to secure by Letters Patent, is—

1. In a centrifugal pump, a hollow rotating driver having a central suction-aperture and a continuous peripheral slot, and provided with wedge-shaped radial partitions or diaphragms of different length and alternating long and short, whereby radial chambers with tapering outer ends are formed, in combination with a fixed receiving-casing encircling the driver and having a continuous receiving aperture or slot in its side opposing the peripheral slot of the driver, substantially as herein described.
- 15 2. In a centrifugal pump, a hollow rotating driver having a central suction-aperture and a beveled or converging inclined rim portion provided with a continuous peripheral slot or opening, and with radial partitions or diaphragms of a wedge shape and alternating long and short, whereby chambers are formed with tapering outer portions, in combination with a fixed annular receiving-casing encircling the driver and having on its inner side a continuous slot or opening opposing the slot or opening of the driver, substantially as herein described.
- 25 3. In a centrifugal pump, a rotating hollow driver having a suction-aperture and a con-

tinuous peripheral discharge-slot, in combination with a fixed annular casing encircling the driver and having in its inner side a continuous receiving opening or slot opposing the peripheral slot of the driver, said receiving-opening being inwardly tapering or funnel-shaped, with its walls projecting inwardly beyond the walls proper of the casing, substantially as herein described.

4. In a centrifugal pump, the rotating hollow driver A, having the central suction-aperture, a, the beveled rim with the continuous peripheral discharge-slot a', and radial partitions a² and a³, wedge-shaped and alternating long and short, whereby radial chambers are formed with tapering outlets, in combination with a fixed annular receiving-casing, B, encircling the driver without touching it, and having on its inner surface a continuous receiving-slot, b, opposing the slot of the driver, said receiving-slot being of an inwardly tapering or funnel shape, all arranged and operating substantially as herein described.

In witness whereof I have hereunto set my hand.

ISAAC P. LAMBING.
